CLAIM

The ornamental design for a rotatable modular connector for a telephone, as shown and described.

DESCRIPTION

FIG. 1 is a perspective view of the rotatable modular connector for a telephone showing my new design;
FIG. 2 is a left side elevational view thereof, the right side being a mirror image;

FIG. 3 is an end elevational view thereof;

FIG. 4 is a top plan view thereof;

FIG. 5 is a bottom plan view thereof;

FIG. 6 is an opposite end elevational view thereof.

FIG. 1

FIG. 6

FIG. 2

FIG. 3

FIG. 4

FIG. 5
